UNITED STATES PATENT OFFICE.

HARRIET E. BINGHAM, OF BATAVIA, NEW YORK.

DESIGN FOR A HAIR-DRIER.

SPECIFICATION forming part of Design No. 30,229, dated February 21, 1899.

Application filed December 17, 1898. Serial No. 699,603. Term of patent 7 years.

To all whom it may concern:

Be it known that I, HARRIET E. BINGHAM, a citizen of the United States, residing at Batavia, in the county of Genesee and State of New York, have invented and produced a new and original Design for a Hair-Drier, of which the following is a specification, reference being had to the accompanying drawings, forming a part thereof.

This design relates to the configuration of a hair-drier, the accompanying drawing being a perspective view of the same.

The distinctive feature of my design consists of the peculiar shape of the body of the hair-drier and the funnel arranged above the body.

Referring to the drawings, A represents the circular base of the hair-drier, B the body surmounting the base, and C the funnel surmounting the body. The body consists of a central enlarged portion a , which is substan-

tially spherical in form, a lower tapering portion a' , extending downwardly from the central portion to the base, and an upwardly-tapering portion a'' , extending upwardly from the central portion to the funnel. The funnel extends from the upper part of the body upwardly and laterally in a curve and flares from its lower end toward its upper end in the form of a trumpet.

³⁰
 d is a pendant arranged on the lower end of the laterally-projecting upper portion of the funnel.

I claim as my invention—

The design for a hair-drier, substantially as herein shown and described.

Witness my hand this 8th day of December, 1898.

HARRIET E. BINGHAM.
